UNITED STATES PATENT OFFICE.

PAUL BURKE, OF GREEN BAY, WISCONSIN, ASSIGNOR TO NORTHWEST ENGINEERING COMPANY, OF GREEN BAY, WISCONSIN, A CORPORATION OF WISCONSIN.

POWER SHOVEL.

Original application filed May 26, 1924, Serial No. 716,000. Divided and this application filed February 9, 1925. Serial No. 7,973.

To all whom it may concern:

Be it known that I, PAUL BURKE, a citizen of the United States of America, and resident of Green Bay, in the county of Brown and State of Wisconsin, have invented new and useful Improvements in Power Shovels, of which the following is a description, reference being had to the accompanying drawings, which are a part of this specification.

1. The invention relates to excavating machines.

In some types of power shovels, using one source of power for both hoisting and thrusting, provision is made for positively thrusting the dipper and its handle outwardly, as by a gear drive or a separate cable, without any cooperative association therewith by the hoisting cable, which is a separate unit. While such mechanisms permit positive outward thrust of the handle, regardless of its position relative to the boom and allow thrusting out to the extreme position, it is to be noted that whatever power is devoted to thrusting effort will involve a simultaneous and corresponding reduction in the power then available for hoisting; that is to say, assume a dipper lowered onto the material to be excavated, and being moved through the material, the resistance encountered being such as to take nearly all the power of the engine, no thrusting taking place, the dipper moving in substantially the arc of a circle; when, as is usually the case, it becomes necessary to thrust further into the bank power must be subtracted from hoisting, which results in a corresponding reduction in the force at the dipper lip and teeth for cutting through the material. This means a reduction in the size of the bite must be made, or perhaps the dipper will have to be returned part way to the starting point and a new bite started because of the demands upon the power plant which, as a practical matter, is generally not provided with excess power. This naturally slows up the digging operation and produces poor and unsatisfactory operation where the digging conditions are difficult.

With that type of rope-thrusting shovel in which thrusting is obtained by or in connection with the hoisting cable and the tension available for hoisting is not reduced while such thrusting action is taking place, the single power plant need not be overpow-

ered since the thrusting effort or the restraining effort from outward motion of the stick occasions no reduction in the net digging effort and the energy balance is maintained, but with such construction as now known, where the stick is long, it usually cannot be projected beyond the boom when above the horizontal for dumping, because forces due to the weight of the bucket and the inward thrust exerted by said hoisting cable prevent this. Furthermore, with such constructions a rapid longitudinal shaking movement cannot be readily imparted to the stick and dipper, which motion is sometimes desirable for the purpose of dislodging a rock or other object with which the dipper and its teeth may be engaged during digging.

This application constitutes divisional subject matter from that of my copending application Serial No. 716,000, filed May 26, 1924, and relates more particularly to that form of my invention in which positive outward thrusting is accomplished by a reversible chain drive associated with a hoisting cable having a thrusting effort on the dipper and dipper handle.

The invention further consists in the several features hereinafter set forth and more particularly defined by claims at the conclusion hereof.

In the drawings:

Fig. 1 is a side elevation view of an excavating shovel embodying the invention;

Fig. 2 is a plan view of the shovel shown in Fig. 1, with the stick shown in section.

In the drawings the numeral 46 designates the boom, which may be of any suitable construction, vertically pivotally attached at its lower end to a rotating base 47 of the machine, which base is of well-known construction. The hoisting drum 48 is loosely mounted on a shaft 49 suitably supported on the rotating base in any well-known manner, and a gear 50 is keyed to said shaft and meshes with a drive pinion 51 on a shaft 52 which is driven in any suitable manner from a prime mover, not shown, on the rotating base. A member 53, here shown in the form of a drum, is loosely mounted on a shaft 54 suitably supported on the rotating base in any well-known manner, and a gear 55 is keyed to the shaft 54 and meshes with a gear 50. A member

56, here shown in the form of a drum, is loosely mounted on the shaft 49 and has a gear 57 formed integral therewith meshing with an idler pinion 58 on a transmission 5 shaft 59, which pinion meshes with a gear 60 formed integral with the drum 53. The hoisting drum 48 is equipped with a clutch 61, of any suitable construction, for connecting it to be driven by the shaft 49 and 10 with a suitable brake 62. The member 53 is equipped with a clutch 63 of any suitable construction for connecting it to be driven by the shaft 54 and with a suitable brake 64. The drum 56 is equipped with a clutch 65, 15 of any suitable construction, for connecting it to be driven by the shaft 49. Thus, the drum 48 and the member 56 may be independently connected with the source of power through their clutches 61 and 65, and 20 the member 53 may be driven in one direction when connected by the clutch 63 to the shaft 54, and in the opposite direction through the gearing connection 57, 58 and 60, it being noted that the clutch 65 may be 25 associated directly with the member 53 and the gear 57 be made fast to the shaft 49 without changing the operation.

A shipper shaft 66 is journalled in bearing brackets 67 on the boom and carries a 30 pinion or gear 68 meshing with a rack 69 affixed to the dipper handle or stick 70 which is slidably mounted in a yoke 71 mounted to swing on and about the shipper shaft 66. The dipper or shovel 72 may be 35 of any suitable construction and is mounted, as usual, at the lower end of the stick. A hoisting and outward-thrusting cable 73, wound around the drum 48 and secured thereto, passes therefrom under a guide 40 sheave 74 on the boom, thence over a sheave 75 loose on the shaft 76 at the outer end of the boom, thence downwardly through a transversely disposed padlock sheave 77 pivotally connected to the dipper, thence upwardly over a guide sheave 78 loose on the shaft 76, thence backwardly to and around a drum 79 keyed to the shaft 66, and the 45 end of said cable is dead-ended on said drum. The member or drum 53 has a 50 sprocket wheel 80 formed integral therewith or secured thereto, which is operatively connected to the sprocket wheel 81 keyed to the shaft 66 by a chain 82.

The boom is adapted to be raised or lowered and held in various positions of vertical adjustment by well-known means, such as cables 83 connecting pulleys 84 to parts on the rotating base.

With this last-described construction, it 60 will be noted that when the drum 53 is prevented from rotating by its brake 64 and the clutch 65 is disengaged and the clutch 61 for the drum 48 is thrown in, thereby connecting said drum with the source of power 65 to turn the same to pull in on the cable 73, the dipper will swing approximately in the arc of a circle of which the shipper shaft 66 is the center. The dipper having been drawn in toward the machine and lowered upon the material to be excavated, and with the 70 brake 64 on member 53 released and with the drum 48 connected to the shaft 49 through the clutch 61, cable 73 is wound in, causing the dipper pivoted about the shaft 66 to swing relative thereto and at the same 75 time, due to the tension produced in said cable, causing the drum 79 to revolve in a clockwise direction and thus rotate the shaft 56 and its pinion 68 through the rack 69 to move the dipper stick 70 lengthwise and outwardly, producing an outward thrusting of the dipper, thus crowding it outwardly into the material to be excavated. If, during this digging operation, it is desired to increase the thrusting force, the clutch 63 80 for the member 53 is thrown in, thereby connecting the member 53 with the source of power through gears 51, 50 and 55, and driving the shipper shaft 66 through the sprockets 80 and 81 and the chain 82 in 85 the same direction as the pull on the cable 73, which causes a turning of the shaft 66 and hence causing additional power to be imparted to the shaft 66 to increase the 90 outward thrusting effect. 95

Furthermore, as the dipper under the action of the hoisting cable is swung upwardly beyond a substantially horizontal position, the tendency of the dipper and its stick to shift inwardly, due to the tension in the 100 hoisting cable and the weight of the dipper and its stick, may be prevented by the release of clutch 63 and the application of brake 64 to the shaft 53 to hold the gear 68 against turning, and by connecting the 105 member 53 with the source of power through the clutch 63 and the gears 51, 50 and 55 the positive outward thrust of the additional drive thus furnished will move the stick outwardly against the forces tending to shift 110 it inwardly, as previously mentioned, so that the dipper will be moved to bring the padlock sheave 77 substantially beyond the point of the boom and the stick substantially above the horizontal. Thus, the drive 115 from the drum 53 assists in thrusting the stick outwardly during digging and in thrusting the stick outwardly during hoisting, or preventing its tendency to shift inwardly under the conditions above described. If it is desired to retract the dipper or move it in toward the boom, throwing out clutches 61 and 63 and throwing in clutch 65 causes the drive from the source 120 of power through the gears 51, 50, 57, 58 and 60, member 53, sprockets 80, 81 and chain 82 to turn the shaft 66 in a counter-clockwise direction, whereby the pinion acts on the rack to move the stick inward or upward relative to the boom. 125 130

From the foregoing description it will be noted that I have provided a construction in which the dipper and its handle may be positively thrust outwardly or inwardly during digging and that the association of the hoisting cable with the outward thrusting means prevents loss of power due to thrusting.

I desire it to be understood that this invention is not to be limited to any specific form or arrangement of parts except in so far as such limitations are specified in the claims or necessitated by the prior art.

What I claim as my invention is:

1. In an excavating machine, the combination with a supporting boom, of a dipper and dipper handle mounted thereon to move lengthwise and swing with respect thereto, of means for moving the dipper and its handle lengthwise in both directions and including a reversible member, and a dipper-hoisting cable associated with said means for conjoint outward thrusting therewith during outward lengthwise movement of said dipper and dipper handle.

2. In an excavating machine, the combination with a supporting boom, of a dipper and dipper handle mounted thereon to move lengthwise and swing with respect thereto, of a reversible drive mechanism associated with the dipper and its handle for moving the same outwardly and inwardly, and a dipper-hoisting cable associated with said mechanism for conjoint outward thrusting therewith during digging.

3. In an excavating machine, the combination with a supporting boom, of a shipper shaft, a pinion on said shaft, a dipper and dipper handle mounted to move lengthwise and swing with respect to the boom and having a rack meshing with said pinion, means for driving said shipper shaft to move the dipper and its handle lengthwise in both directions, a drum on said shipper shaft, and a dipper-hoisting cable associated with said drum for conjoint outward thrusting with said pinion during outward lengthwise movement of said dipper and dipper handle.

4. In an excavating machine, the combination with a supporting boom, of a ship-

per shaft, a pinion on said shaft, a dipper and dipper handle mounted to move lengthwise and swing with respect to the boom and having a rack meshing with said pinion, means for driving said shipper shaft to move the dipper and its handle lengthwise in both directions, and a dipper-hoisting cable also associated with said dipper and dipper handle for conjoint outward thrusting with said pinion during outward lengthwise movement of said dipper and dipper handle.

5. In an excavating machine, the combination with a supporting platform and a boom extending therefrom, of a dipper and dipper handle mounted on the boom to move lengthwise and swing with respect thereto, said dipper handle having a rack, a pinion mounted on the boom and meshing with said rack for moving the dipper and its handle lengthwise in both directions, means mounted on said platform and operatively connected with said pinion for driving it in either direction, a dipper-hoisting cable associated with said pinion for conjoint outward thrusting therewith during outward lengthwise movement of said dipper and dipper handle, and a hoisting drum for said hoisting cable mounted on said platform.

6. In an excavating machine, the combination with a supporting platform and a boom extending therefrom, of a dipper and dipper handle mounted on the boom to move lengthwise and swing with respect to the boom and having a rack, a shipper shaft, a pinion on said shaft meshing with said rack, a sprocket wheel on said shaft, a shaft mounted on said platform and carrying a sprocket wheel, a chain operatively connecting said sprocket wheels, reversible drive means for said last-named shaft whereby to move said dipper and dipper handle lengthwise in both directions, and a dipper-hoisting cable also associated with said dipper and dipper handle for conjoint outward thrusting with said pinion during outward lengthwise movement of said dipper and dipper handle.

In testimony whereof, I affix my signature.

PAUL BURKE.
